[57] CLAIM

The ornamental design for a “wrench socket tray”, as shown and described.

DESCRIPTION

FIG. 1 is a right hand end perspective view of the wrench socket tray according to the present design of this invention showing optional support legs in phantom;

FIG. 2 is a top plan view thereof;

FIG. 3 is a front elevational view thereof; the rear elevational view being the reverse thereof;

FIG. 4 is a right hand end elevational view thereof;

FIG. 5 is a left hand end elevational view thereof; and,

FIG. 6 is a bottom plan view thereof.

The broken line showing of support legs in FIGS. 1, 3, and 4, is for illustrative purposes only and forms no part of the claimed design.
